UNITED STATES PATENT OFFICE.

HERMAN ROTHERMEL, OF HEMPSTEAD, NEW YORK.

COMBINATION PUTTY KNIFE AND PAINT SCRAPER.

Application filed December 27, 1928. Serial No. 328,726.

My invention relates to hand tools and more particularly to a combination putty knife and paint scraper.

An object of the invention is to provide a novel form of holder adapted for fitting engagement over the working edge of a putty knife, said holder being shaped to receive and yieldingly hold the scraping or cutting blade in place.

10 A further object of the invention is to provide a holder in which the scraping or cutting blade is freely removable therefrom without removing the holder from its fitting engagement over the working edge of the putty knife, and in which the holder, together with the scraping or cutting blade, can be freely removed as a unit where and when it is desired to use the putty knife as such.

20 A still further object of the invention is to provide a combination hand tool for glaziers' and painters' use, the parts of which can be separately manufactured and separately sold, or if desired, sold together; one in which the holder, if separately sold, can be used on or in connection with all conventional forms of putty knives; and one in which, when used as a paint scraper, is enhanced in effectiveness due to the flexibility of the putty knife blade.

Other objects and advantages of the invention will be hereinafter set forth.

In the drawings, wherein like reference characters denote like or corresponding parts,

Fig. 1 is a perspective view of the combination tool;

Fig. 2 is a fragmentary plan view showing the relation of the holder to the working edge of the putty knife blade;

Fig. 3 is an edge view of the assembly illustrated in Fig. 2, and

Fig. 4 is an edge view of the tool used as a paint scraper.

45 In the embodiment of the invention selected for illustration, a putty knife of conventional form is shown. It comprises (see Fig. 1) a blade 10 of metal, preferably flexible tool steel, and a handle 11 fastened to the shank 12 of the blade by rivets or other fastening means.

To the working edge of the blade 10 a holder 14 for the scraping or cutting blade

15 is removably fastened. Said holder 14 is preferably formed in one piece. As illustrated in Fig. 3 said holder 14 comprises an intermediate part 16 upon the opposite sides or faces of which pockets 17 and 18 are formed. The pocket 17, which is adapted to receive the scraping or cutting blade 15, is 55 preferably formed by bending the one piece sheet metal stock upon itself, shaping it to the inner end or guard formation as indicated at 19, and flaring its free edge away from the intermediate portion thereof as indicated 60 at 20. Thus shaped, the blade 15 is yieldingly held within said pocket 17 and may be 65 easily and quickly removed or replaced by edgewise or lateral sliding movement.

The opposed or second pocket 18 is similarly formed. The sheet metal stock is reversely bent upon itself and at or near its opposite edge it is indent as indicated at 21 to provide a bearing surface. Such bearing surface, with the putty knife blade inserted 70 in said pocket 18, engages said blade and by its engagement yieldingly holds the holder 14 in place. The open end pockets, it will be noted, open oppositely. If desired, means may be provided to prevent the accidental edgewise movement of the scraping blade.

A combination putty knife and paint scraper thus characterized is advantageous in that the flexibility of the putty knife 75 blade (see Fig. 4) is utilized to advantage when the tool is used as a paint scraper; it is also advantageous in that both the scraping blade and the putty knife blade may be 80 separately removed from engagement within 90 the pockets of the holder as desired; and it is further advantageous in that the scraping or cutting blade (preferably a new or discarded safety razor blade) may be inserted or slipped into the pocket 17 without 95 exerting pressure on or even near its cutting edge. When used as a paint scraper, moreover, the greater the pressure on the putty knife and the greater the pressure on the scraping blade, the more firmly are such 100 parts seated and held in their respective holder pockets.

While I have described my invention in detail in its present preferred embodiment, it will be obvious to those skilled in the art 105 after understanding my invention, that vari-

ous changes and modifications may be made therein without departing from the spirit or scope thereof. I aim in the appended claims to cover all such modifications and 5 changes.

What I claim is:

1. In a hand tool, the combination, of a putty knife, a scraping blade, and a holder for said scraping blade removably carried 10 by the working edge of said knife.
2. In a hand tool, the combination of a flexible blade provided at one end with a non-cutting edge, a holder provided with opposed pockets within one of which said 15 non-cutting edge is adapted to be removably held, and a scraping or cutting blade carried

by said holder and engaging in the other said pocket.

3. In a hand tool, the combination, of a supporting blade provided at one end with 20 a non-cutting working edge, a one piece sheet metal holder bent upon itself to provide opposed open end pockets within one of which the non-cutting edge of said supporting blade is adapted to engage, and a freely 25 removable scraping or cutting blade carried by said holder thru its fitting engagement in the other of said pockets.

In testimony whereof I hereunto affix my signature.

HERMAN ROTHERMEL.
